UNITED STATES PATENT OFFICE.

EDWARD E. BRADLEY, OF STONINGTON, CONNECTICUT, ASSIGNEE TO ATWOOD MACHINE COMPANY, OF STONINGTON, CONNECTICUT, A CORPORATION OF NEW JERSEY.

FEED ROLL FOR SPINNING MACHINES.

Application filed October 18, 1922. Serial No. 595,876.

To all whom it may concern:

Be it known that I, EDWARD E. BRADLEY, a citizen of the United States, and resident of Stonington, in the county of New London and State of Connecticut, have invented a new and useful Improvement in Feed Rolls for Spinning Machines, of which the following is a specification.

20 following is a specification:
This invention consists in certain improvements in the construction, form and arrangement of the several parts of the attachment, whereby novel means are provided for automatically separating the turns of the thread as it passes around the feed roll
25 and its adjacent member, to prevent the fraying, roughing and breaking of the thread, due to the sawing of one turn of the thread upon another turn thereof.

My invention more specifically comprises
20 a holder that carries the feed roll and an
adjacent member having an inclined sur-
face, which member may be an idler roller
around which the thread is passed, the mem-
ber being preferably removable so that it
25 may be readily renewable.

Practical embodiments of my invention are represented in the accompanying drawings, in which—

Fig. 1 represents a side view of one embodiment of my invention.

Fig. 2 represents a front view of the same.
Fig. 3 represents a front view of a modified form of attachment, and
Fig. 4 represents a side view of the same.

Fig. 4 represents a side view of the same, 86 The lifting rod of the stop motion is denoted by 1. This rod carries the usual hook arm 2 for gathering the threads together as they pass to the feed roll. A suitable holder 3 is secured to the lifting rod 1, which holder carries a horizontally arranged feed roll 4 and a member having an inclined surface around which the thread is passed, which member is located over and in proximity to the feed roll.

43 In the embodiment shown in Figs. 1 and 2, the member having the inclined surface is shown as a removable inclined idler roller 5 located over and in proximity to the feed roll.

30. The feed roll 4 is provided with a gear 11 which meshes with a gear 12 on the driving shaft 13. The holder 3 is developed into a shield 6 which serves to prevent the waste from accumulating around the driving shaft.

13. This shield also overlaps the inner ends ⁵⁵ of the feed roll 4 and idler roller 5.

In the form shown in Figs. 3 and 4, the member 7 having the inclined surface is located within an inclined fixed tube 8 secured at 9 to the holder 3, a pin 10 passing through the outer end of the tube serving to removably hold the member 7 in position within the tube. This member 7 may be either fixed or rotatable. In the present instance, it is shown as rotatably mounted in the tube 8, and it may be a rod of porcelain or other suitable material.

It will be seen that by reason of the group of threads passing around the member having the inclined surface, the turns of the thread will be automatically separated, thus preventing damage to the thread.

It is evident that various changes may be made in the construction, form and arrangement of the several parts without departing from the spirit and scope of my invention, hence I do not wish to limit myself to the particular embodiments herein shown and described, but—

What I claim is:

1. In a device of the character described, a feed roll of one diameter, and an inclined idler roller of relatively smaller diameter around which the thread is passed.

2. In a device of the character described, a feed roll of one diameter, and an inclined idler roller of relatively smaller diameter located over and in proximity to the feed roll around which idler roller the thread is passed.

3. In a device of the character described, a feed roll of one diameter, and a removable inclined idler roller of relatively smaller diameter around which the thread is passed.

4. In a device of the character described, a feed roll of one diameter, and a removable inclined idler roller of relatively smaller diameter located over and in proximity to the feed roll around which idler roller the thread is passed.

5. In a device of the character described, a feed roll of one diameter, its driving gears, a member of another diameter having an inclined surface around which the thread is passed, and a holder for the feed roll and member, said holder being developed into a shield for the feed roll driving gears. 165

6. In a device of the character described,

223
a feed roll of one diameter, its driving gears, an inclined idler roller of relatively smaller diameter around which the thread is passed, and a holder for the feed roll and idler roller, said holder being developed into a shield for the feed roll driving gears.

7. In a device of the character described, a feed roll of one diameter, its driving gears, a removable inclined idler roller of relatively smaller diameter around which the thread is passed, and a holder for the feed roll and idler roller, said holder being developed into a shield for the feed roll driving gears.

In testimony, that I claim the foregoing as my invention, I have signed my name this ninth day of October, 1922.

EDWARD E. BRADLEY.
